(57) **CLAIM**

The ornamental design for saber ornamentation, as shown and described.

DESCRIPTION

FIG. 1 is a perspective view of saber ornamentation showing my new design;

FIG. 2 is a front elevational view thereof;

FIG. 3 is a perspective view of a second embodiment of saber ornamentation; and,

FIG. 4 is a perspective view thereof with a table shown in broken lines as environmental elements.

The views of the saber ornamentation not shown form no part of the claimed design. The broken lines depicting an eagle head and scroll ornamentation represent environmental elements only and form no part of the claimed design. The broken lines depicting a table in FIG. 4 represent environmental elements only and form no part of the claimed design.

1 Claim, 4 Drawing Sheets
